UNITED STATES PATENT OFFICE.

THOMAS HILL, OF JERSEY CITY, NEW JERSEY.

DUMPING-WAGON.

SPECIFICATION forming part of Letters Patent No. 678,470, dated July 16, 1901.

Application filed December 6, 1900. Serial No. 38,854. (No model.)

To all whom it may concern:

Be it known that I, THOMAS HILL, a citizen of the United States, and a resident of Jersey City, in the county of Hudson and State of New Jersey, have invented certain new and useful Improvements in Dumping-Wagons, of which the following is a specification.

The invention relates to improvements in dumping-wagons, and pertains more particularly to the novel pedestal construction hereinafter described and claimed, adapted to receive the trunnions which project from the sides of the vehicle-body.

The invention will be fully understood from the detailed description hereinafter presented, reference being had to the accompanying drawings, in which—

Figure 1 is a side elevation, partly broken away, of a cart equipped with a pedestal construction embodying the invention. Fig. 2 is a central vertical longitudinal section, on an enlarged scale, of the pedestal construction and its supporting-frame. Fig. 3 is a horizontal longitudinal section of same on the dotted line 3 3 of Fig. 2. Fig. 4 is a detached top view of the longitudinal bar which bears upon the springs and receives the trunnion. Fig. 5 is a bottom view of same, and Fig. 6 is a bottom view of one of the pedestal-caps.

In the drawings, 10 designates the usual wheels, 11 the side frames, which extend forward to form the booms 12, and 13 the cart or vehicle body, also of usual construction, having the trunnions 14 projected laterally from its sides and constituting the pivotal points on which the said body may turn rearward when it is desired to dump the same. Upon the side frames are bolted the pedestal structures made the subject of this application and each comprising the base-plate 15, the hollow pedestals 16 16, the springs 17 within said pedestals, the longitudinal bar 18, having the bearing 19 for the trunnion 14, and at its ends resting on said springs 17, the caps 20 on the upper ends of said pedestals 16, and the rods 21, which extend centrally through said pedestals 16, springs 17, ends of bar 18, and caps 20.

The base-plate 15 is of suitable size and is in one integral casting with the hollow pedestals 16 16, the latter when in the casting being open both at their upper and lower ends.

The plate 15 is secured upon the side frames 11 by means of bolts 22 and the aforesaid rods 21, and said plate being integral with the hollow pedestals 16 16 supports the same. The pedestals 16 16 are cylindrical in cross-section and have at their facing sides the vertical slots 23, which are encompassed at their sides and bottom by the flanges 24, which afford broad wall-surfaces to said slots 23 and also strengthen the pedestals.

Within the pedestals 16 16 are confined the coiled springs 17, whose lower ends bear upon the side frames 11 or upon small protecting-plates 25, placed on said frames and within the lower ends of said pedestals. The springs 17 support upon their upper ends the bar 18, whose middle portion contains the bearing-aperture 19 and whose ends are within the pedestals 16 and of special formation in that they have the circular hubs 26 on their lower sides to enter the upper ends of the springs 17, and the encompassing edge flanges 27 on their upper sides to afford extended guiding-surfaces for the ends of the bar 18 within the pedestals and also to strengthen said ends. The ends of the bar 18 are circular and substantially correspond at their edges with the inner walls of the pedestals 16, and said ends of the bar 18 are wider than the slots 23, and hence could not be pulled horizontally outward through said slots, in which, as is apparent, the bar 18 is adapted to have a vertical movement.

Upon the upper ends of the pedestal 16 are the caps 20, which have a polygonal central aperture 28 and two concentric edge flanges 29 29 to pass upon and hold between them the upper edges of the pedestals 16, said flanges 29 29 affording strength to the caps 20 and effectually resisting any tendency of said caps to move laterally when the cart is in use. The caps 20 close the upper ends of the pedestals 16 and also the upper ends of the slots 23, and they retain the ends of the bar 18 securely within the pedestals 16 16 without interfering with the vertical movement of said bar.

The caps 20 are fastened upon the upper ends of the pedestals 16 by means of the bolt-rods 21, which pass downward through the caps 20, the ends of the bar 18, the springs 17, and the side frames 11, said bolt-rods 21 hav-

ing a head to bear upon the upper end of the caps 20 and being threaded at their lower ends to receive the securing-nuts below the lower surface of the side frames 11. The upper portions of the bolt-rods 21 are provided with the polygonal surfaces 30 to engage the walls of the apertures 28 in the caps 20, the said polygonal surfaces 30 in connection with the walls of the apertures 28 constituting means for preventing the turning of the bolt-rods 21. It will be observed upon reference to Fig. 2 that the bolt-rods 21 pass downward centrally through the hubs 26 on the lower sides of the ends of the bar 18, and hence the said rods 21 aid in guiding the bar 18 during its vertical movement, the walls of the apertures through the hubs 26 forming extended guiding-surfaces to move on the rods 21.

The trunnions 14 at the opposite sides of the body 13 are retained within the bearing-apertures 19 of the bars 18, and hence the said trunnions have a spring-bearing by reason of the support afforded to the bar 18 by means of the springs 17, and during the movement of the vehicle the bar 18 will have a vertical play, being guided in its movement by the walls of the slots 23, the surfaces of the bolt-rods 21, and the inner walls of the pedestals 16, the said bar 18, while being permitted to have a vertical movement, being effectually prevented from having endwise movement.

The construction hereinbefore presented is of that durable character which enables it to withstand the severe usage to which the carts are ordinarily subjected, and in addition the structure is such that it embraces the minimum number of parts and is capable of being constructed and applied in a comparatively inexpensive manner. It is to be observed also that the details of the parts of the pedestal structure are so disposed and arranged with relation to one another as to prevent endwise thrusts against the bar 18 from having any prejudicial effect on the structure as a whole, the strains following any endwise thrusts on the bars 18 being so distributed through the structure as a whole as to enable the structure to withstand the same.

50 What I claim as my invention, and desire to secure by Letters Patent, is—

1. In combination with the running-gear and vehicle-body, the latter having the side trunnions 14, the pedestal structure secured to the side frame and comprising the cylindrical pedestal members 16, the base-plate 15 integral with said pedestal members 16, the springs 17 within said pedestal members, the longitudinal bar 18 having its ends within 55 said pedestal member 16 and upon said springs 17, and also having intermediate said pedestal members 16 the bearing-aperture 19 for the side trunnion 14, the caps 20 upon the upper ends of the said pedestal members 16, and 60 the rods 21 extending through said caps 20, the ends of said bar 18, said springs 17 and said side frames; substantially as set forth.

2. In a vehicle, the running-gear and body 13, the latter having the side trunnions 14, combined with the pedestal structure secured to the side frames and adapted to receive said trunnions, said pedestal structure comprising the cylindrical pedestal members 16, 16, having at their facing sides the vertical elongated guiding-slots 23, the springs within 70 said pedestal members 16, caps closing the upper ends of said pedestal members 16, and the longitudinal bar 18 having the bearing-aperture 19 for the trunnion 14 and having its end portions extended through said vertical slots 23 and bearing upon the said springs, the ends of said bar 18 within the pedestal members 16 being greater in width than said slots 23 and affording guiding-surfaces for said bar; substantially as set forth. 80

3. In a vehicle, the running-gear and body, the latter having the side trunnions 14, combined with the pedestal structure secured to the side frames and adapted to receive said trunnions, said pedestal structure comprising 90 the cylindrical pedestal members 16, 16, having the vertical elongated slots 23 on their facing sides, the springs 17 within said pedestal members, the caps 20 upon the upper ends of said pedestal members, the longitudinal bar 18 having the bearing-aperture 19 for the trunnion 14, and extending through said slots 23, to bear upon said springs 17, and the rods 21 extending downward through said caps, the ends of the said longitudinal 95 bar 18, said springs 17 and said side frames, the rods 21 serving to aid in holding the pedestal structure upon the side frames and to guide said bar 18; substantially as set forth.

4. In a vehicle, the running-gear and body, the latter having the side trunnions 14, combined with the pedestal structure secured to the side frames and adapted to receive said trunnions, said pedestal structure comprising the pedestal members 16, 16, having the elongated slots 23 in their facing sides, the springs 17, within said pedestal members 16, the longitudinal bar 18 passing within said slots 23 and having the bearing-aperture 19 to receive said trunnion 14, and also having its end portions 110 within the pedestal members 16 to bear upon said springs 17 and possessing the hubs 26 to enter the upper ends of said springs and the guiding-flanges 27 to guide against the inner walls of said pedestal members 16, and removable caps upon the upper ends of said pedestal members 16 to close the upper ends of said slots 23 and the upper ends of said pedestal members; substantially as set forth. 115

5. In a vehicle, the running-gear and body, the latter having the side trunnions 14, combined with the pedestal structure secured to the side frames and adapted to receive the said trunnions, said pedestal structure comprising the pedestal members 16, 16, having 120 the elongated slots 23 at their facing sides, the springs 17 within said pedestal members, the longitudinal bar 18 having the bearing-aperture 19 to receive the trunnion 14 and be- 125

ing confined within said slots 23, and also having its end portions within the pedestal members 16 and upon the springs 17, the caps 20 closing the upper ends of said slots 23 and 5 the upper ends of said pedestal members 16 and provided with the concentric flanges 29, 29, to receive between them the upper edges of said pedestal members, and the rods 21 passing through said caps 20, and guiding the 10 ends of said bar 18; substantially as set forth.

6. In a vehicle, the running-gear and body, the latter having the side trunnions 14, combined with the pedestal structure adapted to receive said trunnions, said pedestal structure 15 comprising the base-plate 15 adapted to receive the securing-bolts 22, the pedestal members 16, 16, having the slots 23 in their facing sides and being integral with said base-plate 15, the springs 17 within said pedestal

members 16, the longitudinal bar 18 in one 20 integral piece and having its enlarged end portions confined within said pedestal members 16 and upon said springs 17 and having intermediate said pedestal members 16 the bearing-aperture 19 for the trunnion 14, caps 25 closing the upper ends of said pedestal members 16 and said slots 23, and the rods 21 extending downward through said caps, the ends of the said bar 18, said springs 17 and said side frames; substantially as set forth. 30

Signed at New York, in the county of New York and State of New York, this 5th day of December, A. D. 1900.
